UNITED STATES PATENT OFFICE

HENRY W. WILD, OF WATERBURY, CONNECTICUT, ASSIGNOR TO SCOVILL MANUFACTURING COMPANY, OF WATERBURY, CONNECTICUT, A CORPORATION OF CONNECTICUT

LIP-STICK HOLDER

Application filed May 24, 1927. Serial No. 193,760.

This invention relates to certain improvements in lipstick holders, that is, holders of small size designed to carry lipsticks, eyebrow pencils and the like.

5 It is the especial object of the present invention to produce a holder of this character in which there are provided two containers which are closed at their outer ends and open into a central sleeve at their inner ends, the 10 containers being pivoted to this sleeve independently so that the article may be used for carrying different small articles and each container may be used separately from the other or both may be opened for use at the 15 same time.

It is a further object of the invention to produce such a container which will have means whereby it may be secured to a chain or have secured to it a vanity case, bracelet 20 or other like article.

It is a further object of the invention to produce a container of few parts so that it can be cheaply made and easily assembled, and one in which the containers will be maintained in removable engagement with the central sleeve so as to be prevented from accidental opening and consequent possible loss 25 of the contents.

With these and other objects not specifically referred to in view, the invention consists in certain novel parts, arrangements and combinations which will be described in connection with the accompanying drawings and the novel features pointed out in the claims 30 hereunto annexed.

Referring to these drawings,—

Figure 1 is a side elevation of the improved holder with the individual containers shown in open position;

40 Figure 2 is a side view of the holder shown in Figure 1 showing the parts closed;

Figure 3 is a view looking down on the arrangement shown in Figure 1 with the parts in the same position;

45 Figure 4 is a detail view similar to Figure 1, partly in section, on a much enlarged scale to show certain details of construction, and

Figure 5 is a detail view of the preferred construction for hinging the parts together.

50 Referring now to these drawings, the im-

proved holder will include a central sleeve or collar 1 which is hollow. Pivotally secured to this central sleeve, at opposite side edges, is a pair of independent containers 2, 3, having outer ends 4 closed and their inner ends 5 open, these inner ends opening into the central sleeve.

These containers are small so that the whole article may be conveniently carried in a lady's handbag or other convenient receptacle, and are capacitated to hold a lipstick, an eyebrow pencil or, if desired, a small bottle of perfume. Each of the containers is provided near its inner end with a bead 6, hereinafter referred to, and above the bead with a short flange 7 which has frictional engagement with the inner wall of the sleeve. Preferably means such as a nib 8 is provided on the flange for increasing the frictional engagement between the flange and the wall of the sleeve so that the parts are held securely in position.

These two containers are pivotally secured to the edges of the sleeve by suitable hinges and, in the best constructions, these hinge members will be located at the bead 6 before referred to. In the particular form shown, the bead of each container is formed with a pair of narrow slots (see Figure 5) marked 9 leaving a web 10 between them. The central sleeve at each side is formed with a projection which is bent to pass through the slots 9 and engage the web 10, as shown in Figure 4, this projection being marked 11.

With this construction the containers may be hinged in place without the use of any pintle wire and thus a very economical construction provided and one which permits easy assembly of the parts.

The holder as a whole may, if desired, be provided with means by which it may be attached to a chain or have attached thereto a vanity box or the like. Such means, of course, may be varied but in the particular construction shown there is provided a ring 12 which is secured to a staple 13, the legs 14 of which are passed through an opening 15 formed in the wall of the sleeve and bent up against the wall so as to firmly hold the ring in position.

In the container construction as described, it will be observed that the central sleeve acts as a connecting piece for the two containers and also serves as a protection, guarding the user from the particular cosmetic which is not in use at the time the other container is moved away from the sleeve, and its contents are being employed.

It will be observed further that the separate containers 2, 3, are longer than the sleeve so that when the article is suspended from the ring, the weight of the containers tends to keep them in engagement with the connecting sleeve, this thus assisting the nibs in holding the parts against accidental displacement.

While the invention has been shown and described in its preferred form, it will be understood that certain changes and variations may be made in the shape of the containers and in the particular way in which they are secured to the central sleeve and that such changes are within the invention as defined in the appended claims.

What I claim is:

- 25 1. In a lipstick holder, the combination of a central hollow guard sleeve, a pair of lipstick containers each longer than the sleeve closed at their outer ends and opening at their inner ends into the sleeve, a bead at the inner end of each container, slots in each bead, and a projection on the sleeve at each slot passing through the slots and turned over to form a knuckle for hinging the containers to the edges of the sleeve.
- 35 2. In a lipstick holder, the combination of a central hollow guard sleeve, a pair of lipstick containers each longer than the sleeve closed at their outer ends and opening at their inner ends into the sleeve, a bead at the inner end of each container, a flange above the bead for frictional engagement with the walls of the sleeve, and means for hinging the containers at the bead to opposite edges of the sleeve.
- 45 3. In a lipstick holder, the combination of a central hollow guard sleeve, a pair of lipstick containers longer than the sleeve closed at their outer ends and opening at their inner ends into the sleeve, and hinge means connecting the holders at opposite sides of the sleeve.

In testimony whereof, I have hereunto set my hand.

HENRY W. WILD.
